[57] CLAIM

The ornamental design for an arm rest for guitar or
similar musical instrument, as shown and described.

DESCRIPTION

FIG. 1 is a top plan view of an arm rest for guitar or
similar musical instrument showing my new design;

FIG. 2 is a bottom plan view thereof;

FIG. 3 is a right side elevational view thereof;

FIG. 4 is a left side elevational view thereof; and

FIG. 5 is a front elevational view thereof, the rear being
a mirror image.

FIG. 1

FIG. 3

FIG. 2

FIG. 4

FIG. 5
